GRINDING MACHINE

Albert D. Mizzy, New York, N. Y., assignor to
Eleanor Mizzy, New York, N. Y.

Application June 2, 1942, Serial No. 445,417

4 Claims. (Cl. 51—134)

This invention relates to grinding machines, and more specifically to a machine for grinding the tips of hypodermic injection needles or similar objects. The invention has for its principal object the mass grinding of such objects as a constant, continuous process.

To accomplish the above result there is provided a holder for the needles which is designed to be automatically closed after the needle is in holding position and automatically released to permit withdrawal of the needle when the grinding operation is completed and to permit reception of an unground needle.

It is a further object of this invention to provide a grinding machine for hypodermic injection needles in which the bevel on the needle tip will be determined independently of the operator and will therefore be uniform for all needles.

Still another object of this invention is to provide a grinding machine whereby needles of different lengths may be ground in the same machine.

Further objects and advantages of this invention will become apparent in the following description thereof.

In the accompanying drawing,

Fig. 1 is a plan view of a modified form of my invention.

Fig. 2 is a section taken substantially on the line 2—2 of Fig. 1.

Fig. 3 is a section taken substantially on the line 3—3 of Fig. 2.

Fig. 4 is a section taken substantially on the line 4—4 of Fig. 3.

In the form of this invention disclosed in Figs. 1 to 4 inclusive, there is shown a machine which is adapted for the grinding of needles of various lengths. In this form, the stop which determines the projection of the needle point through the chuck arm is not the head of the needle, since this would mean that needles of various lengths would project different distances through the chuck arm. Instead, the stop is positioned at the forward end of the needle and adapted to engage the point of the needle at a fixed distance of projection beyond the chuck arm. Thus needles of different lengths would have their tips at a constant point relative to the chuck arm but would extend rearwardly to varying distances. For this purpose, the turret T' carries a plurality of chucks H, positioned around the periphery thereof, and having a spring-pressed plunger 50 adapted to engage a fixed cam A' which presses the plunger outwardly, in this case, against the action of spring 51, to move the perforation 52

extending through the plunger away from the end of chuck arm 53. This releases the pressure on any needle which is in position within the perforation 52 and permits the needle to be withdrawn or inserted. When the plunger head 55 moves out of engagement with cam A', the compression spring which is positioned between the chuck arm and the piston head pushes the piston inwardly to bring the needle firmly against the end of chuck arm 53 and thus cause the needle to be held firmly within perforation 52.

To permit needles of different lengths to be ground, there is provided a stop member 60 designed to project into the path of the needle 31 when it is in position within perforation 52, so that the tip of the needle can extend no further than the stop 60. Thus, no matter how long the needle may be, it will project forwardly through the perforation 52 a constant distance, while the needles will extend rearwardly to various distances, depending upon their length. The stop 60 is pivotally mounted at 62 on the turret T' and is in lowered position throughout the interval that the plunger head 55 is in engagement with cam A'. It is during this interval that the ground needle is withdrawn and an unground needle is inserted in position. The unground needle is inserted in position, this position being the one where the needle point has reached the stop 60 and therefore is projecting through perforation 52 for a constant distance irrespective of its length. The stop 60 is effective throughout the period that plunger head 55 engages cam A' and for the distance beyond that point during which the plunger 50 has moved inwardly to grip the needle firmly against the end of chuck arm 53. It is now no longer necessary to have the stop 60 in position, because the needle is firmly held with its point projecting at a fixed distance through the perforation 52, and, moreover, the stop must be moved out of the way before the needle reaches the grinding wheel surface so that the needle tip may be ground. Therefore, just before the needle reaches the grinding wheel, a fixed cam 70 is provided which engages under a projection 71 of the stop 60 to lift said stop around its pivot 62 out of engagement with the tip of the needle to the dotted line position shown in Fig. 7. Thus, while the needle is traversing the grinding wheel G, the stop is in ineffective position, but when the needle has passed beyond the grinding wheel, in other words, when the grinding operation is completed, the stop again drops to its lowered position because projection 71 rides off the cam

70 and the stop is now in effective position so that when the head 55 of plunger 50 engages cam A' to move the plunger 50 outwardly and thus release the needle, the needle will be held in its position and will not drop further through the perforation.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other equivalent means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. A grinding machine for hypodermic needles and the like, comprising a rotatable turret, a holder carried by said turret for holding the needle to be ground, said holder having means for releasably holding the needle, a grinding element, means whereby said holder supports needles of various lengths with the ends to be ground in constant relation to the grinding element, said means comprising a pivoted stop in predetermined relation to said holder and adapted to engage the end of the needle to be ground, and means including a cam adapted to engage said stop to move the same out of engagement with the end of the needle to be ground while the needle is in cooperative relation to said grinding element and to release said stop to render the same again effective to engage the end of the needle when the needle passes out of cooperative relation to said grinding element.

2. A grinding machine for hypodermic needles and the like, comprising a rotatable turret, a holder carried by said turret for holding the needle to be ground, means whereby said holder supports needles of various lengths with the ends to be ground in constant relation to the grinding element, said means comprising a pivoted stop in predetermined relation to said holder and adapted to engage the end of the

needle to be ground, means including a cam adapted to engage said stop to move the same out of engagement with the end of the needle to be ground while the needle is in cooperative relation to said grinding element and to release said stop to render the same again effective to engage the end of the needle when the needle passes out of cooperative relation to said grinding element, and means adapted to engage said holder after the needle passes out of cooperative relation to said grinding element for releasing said needle.

3. A grinding machine for hypodermic needles and the like comprising a rotatable turret, a holder carried by said turret for holding the needle to be ground, a grinding element so positioned that rotation of said turret causes the needle to traverse said element, means whereby said holder supports needles of various lengths with the ends to be ground in constant relation to the grinding element, said means comprising a stop carried by said turret in predetermined relation to the holder, said stop being movable to effective and ineffective positions, means for normally holding said stop in effective position in engagement with the end of the needle to be ground, and stationary means adapted to engage said stop to move it to ineffective position while the needle is in cooperative relation to said grinding element.

4. A grinding machine for hypodermic needles and the like comprising a rotatable turret, a holder carried by said turret for holding the needle to be ground, a grinding element so positioned that rotation of said turret causes the needle to traverse said element, means whereby said holder supports needles of various lengths with the ends to be ground in constant relation to the grinding element, said means comprising a stop carried by said turret in predetermined relation to the holder, said stop being movable to effective and ineffective positions, means for normally holding said stop in effective position in engagement with the end of the needle to be ground, stationary means adapted to engage said stop to move it to ineffective position while the needle is in cooperative relation to said grinding element, and means adapted to engage said holder after the needle passes out of cooperative relation to said grinding element for releasing said needle.

ALBERT D. MIZZY.
